UNITED STATES PATENT OFFICE

REGINALD TAYLOR, OF LIVERPOOL, AND CHARLES EDMUND BEALE, OF LONDON, ENGLAND, ASSIGNORS TO ASSOCIATED TELEPHONE AND TELEGRAPH COMPANY, OF CHICAGO, ILLINOIS, A CORPORATION OF DELAWARE

TELEPHONE SYSTEM

Application filed January 20, 1930, Serial No. 421,940, and in Great Britain February 12, 1929.

The present invention relates to telephone systems and is more particularly concerned with arrangements for establishing connections over inter-exchange junction lines. Such junctions are frequently of high resistance and provision has hitherto been made for some means of junction compensation or impulse correction in order to ensure satisfactory operation of the impulse responding apparatus at the incoming exchange. Such arrangements are, however, not always entirely satisfactory and it is an object of the present invention to provide improved circuit arrangements for extending inter-exchange connections.

According to one feature of the invention an automatic numerical switch is arranged to be operated over an inter-exchange trunk line by impulses transmitted over the conductors of the trunk line in parallel and to repeat subsequent impulses to effect the operation of a succeeding switch.

According to another feature of the invention an automatic numerical switch is arranged to be set by incoming impulses and to repeat subsequent impulses over the outgoing speaking conductors, the incoming and outgoing speaking conductors being connected together only when a special signal is received back over the outgoing speaking conductors.

According to a further feature of the invention in a telephone system including an impulse repeater situated at the outgoing end of an inter-exchange trunk line, a relay in the repeater is arranged to be operated either when busy conditions are encountered by the switch at the incoming end or when the called subscriber replies.

The invention will be better understood by referring to the following specification which taken in conjunction with the accompanying drawings discloses one method of carrying the invention into effect. It will be understood, however, that this is given by way of example only and that various modifications may be made in the circuit details by those skilled in the art without departing from the spirit of the invention.

Referring now to the accompanying drawings:

Fig. 1 shows a repeater circuit arranged to repeat impulses received over a loop circuit over the two conductors of an inter-exchange trunk line in parallel.

Fig. 2 shows an incoming selector repeater circuit situated at the other end of the inter-exchange trunk line and arranged to respond to the impulses transmitted over the two conductors in parallel and to repeat corresponding impulses in a loop circuit.

A detailed description of the operation of the apparatus shown in the drawings will now be given; when the repeater shown in Fig. 1 is seized over conductors 10 and 11 a circuit will be closed for impulse accepting relay A as follows: earth at armature 12 of relay BR, lower winding of relay A, contacts associated with armature 13, conductor 11, calling loop, conductor 10, contacts associated with armature 14', upper winding of relay A to battery. Relay A operates over the foregoing circuit and at armature 14 closes the circuit to the upper winding of the guard relay B, and upon the operation of the latter relay earth is connected by way of armature 15 to the release trunk conductor 16 in order to mark the repeater busy; due to the operation of relay A, earth is extended over armatures 14 and 62 to operate relay CR which short-circuits its lower winding to render it slow to release. At armature 17 earth is extended via armature 18 to operate busy control relay BC the function of which relay will be described later, while at armatures 19 and 20 the following junction circuit is completed: battery, low resistance 34, armatures 21, 22 and 23, upper winding of relay I, armatures 24, 19 and 25, conductor 26, armatures 27 and 28, upper winding of the impulse accepting relay A2, armature 29 to earth, and similarly a branch circuit may be traced from battery via the lower winding of relay I, armatures 20 and 30, conductor 31, armature 32, lower winding of relay A2, armature 33 to earth. Consequently the impulse accepting relay A2 of the incoming selector will be operated over both junction lines in parallel, but it must be mentioned that in this

100

particular instance the coils of relay I in the repeater are connected in opposition so that the relay will not operate at this time.

Upon the operation of relay A2, relay B2 will be operated over armature 37 thereby at 5 armature 36 preparing the impulsing circuit to the vertical magnet V. Upon the reception of the first series of impulses relay A in the repeater will respond and at its armature 22 cause said impulses to be repeated to relay A2 in the incoming selector over the circuit previously traced, whereupon the following circuit will then be completed to the vertical magnet V: earth, armatures 37, 36, 38, 10 39, winding of vertical magnet V to battery, and in parallel thereto via the winding of relay C to battery. The vertical magnet operates and raises the shaft and wipers one step each time it operates; on the first vertical 15 step the off-normal springs N are operated thus preparing the circuit to the release magnet Z and also completing the following initial energizing circuit to the test relay G: earth at armature 40 of relay B2, armature 41, armature 42, operated off-normal springs N, winding of relay G to battery. Accordingly, relay G is operated and thereupon completes a locking circuit by way of its 20 operated armature 43 and the interrupter springs 44, and at contact 73 completes a circuit for relay CB which operates and prepares a locking circuit for itself at armature 55. It must be mentioned that both relays B2 and C remain operated during the impulsing due to their slow releasing feature. 25 When the dialled impulse series is completed, relay A2 will be held energized and when relay C releases after a short time interval, rotary magnet R energizes over the following 30 circuit: earth, armature 40 of relay B2, armatures 41 and 42, armature 45, winding of the rotary magnet R to battery. The operation of the rotary magnet causes the shaft to be rotated until the wipers engage with the first set of bank contacts whereupon the 35 rotary interrupter springs 44 are opened, thus opening the holding circuit to the test relay G. Upon the release of the test relay G the circuit is also opened to the rotary magnet R at armature 45 which also restores; if the first set of bank contacts tests busy, wiper 46 will encounter earth and the following 40 circuit will be completed to the test relay G: earth at wiper 46, armature 47, contacts associated with armature 48, interrupter 45 springs 44, operated off-normal springs N, winding of test relay G to battery. Consequently relay G will again complete the 45 circuit to the rotary magnet R and the wipers will accordingly be moved into engagement with the next set of bank contacts. It will be appreciated during the alternate operation of the test relay G, the slow relay CB will remain energized due to the effect of 50 the copper slug on its core. The wipers of

the switch will be automatically rotated over the bank contacts until an idle line is encountered whereat, upon the release of the test relay G consequent upon its disconnection at 55 the rotary interrupter springs, and the rotary magnet R consequent upon its disconnection at armature 45, the following circuit will be completed to the switching relay H: Earth, armature 34 of relay B2, winding of relay H, contacts associated with armature 48, interrupter springs 44, operated off-normal springs N, winding of relay G to battery. It must be mentioned here that due to the limitation of current in the circuit by the comparatively high resistance of the switching 60 relay H, relay G does not operate at this time.

Upon the operation of relay H, earth by way of armature 47 is extended to wiper 46 in order to busy the selected connection, while the following loop circuit is also completed to 65 the impulse accepting relay of the switch ahead; earth through upper winding of impulse accepting relay, wiper 49, armatures 50 and 51, winding of relay I2, left-hand winding of polarized relay D2, armature 52, wiper 53 to battery through lower winding of impulse accepting relay. Relay I2 operates over the foregoing circuit and at its armature 54 maintains the slow releasing relay CB energized via armature 55.

Upon the reception of subsequent series of impulses, relay A2 will again be operated over the parallel circuit, whereat said impulses will then be repeated at armature 51 over the loop circuit previously traced to the switches 100 ahead. When the desired connection has been established and the called subscriber answers, current flow in the calling loop is reversed by the last switch in the train and in consequence the polarized relay D2 operates and completes the following circuit: earth, armature 40 of relay B2, armatures 56 and 57, winding of relay AD to battery. Relay AD thereupon operates and provides a locking 105 circuit for itself by way of armatures 58 and 47, and wiper 46 to earth fed back from the final selector, at the back contacts of armatures 27 and 32, relay AD disconnects relay A2 which thereupon releases and disconnects relay B2 which in turn releases, and at the 110 front contacts of armatures 27 and 32 the speaking circuit through the repeater and selector is completed.

Battery and earth connections from the final selector will now be connected over the junction lines to the repeater, whereupon relay I operates and at armature 59 extends earth via armature 60 to the winding of relay IA. Relay IA thereupon operates and at its light armature 61 closes a locking circuit for itself and at armatures 21 and 23 completes the following inductive loop circuit across the junction lines; conductor 26, armatures 25 and 19, left-hand winding of relay D, armatures 23, 22 and 21, upper and lower 130

windings of relay I in series, armatures 20 and 30, conductor 31. Relay I remains operated since its windings are now aiding one another and relay D operates its armature 62 due to the reversed battery from the final selector switch, thereby completing a circuit to relay DA. The operation of relay DA causes the direction of battery to be reversed around the calling loop at armatures 13 and 14' and it will be noticed that during the reversal period a comparatively high resistance 63 is connected across the calling loop by way of armatures 64 and 65, thereby reducing the clicks produced in the receivers of the calling and called subscribers; relay CR releases after its slow period has elapsed in order to remove the shunting effect of resistance 63. Consequent upon the operation of relays IA and I, relay BC will be held operated from earth, armature 17, armatures 59 and 60, armature 66, winding of relay BC to battery.

Assuming now that the line of the wanted subscriber tests busy or that all the lines in the selected level of a succeeding selector test busy, the usual busy flash conditions will be set up by the operation of cam springs at the group selector or the busy relay at the final selector switch; battery is thereby connected to both trunk conductors as a result relay I2 will release and in turn open the holding circuit to relay CB at armature 54. Relay CB accordingly releases and at armature 67 completes a circuit to relay AD which operates and effects the connecting through of the lines as already explained. When battery and earth are again connected to the trunk conductors at the conclusion of the flash period, relay I in the repeater circuit will be operated thereby causing relay IA to be operated and performing identical functions to that already described for a normal call. Consequently, upon the reception of the next battery flash period, relay I will release and at armature 59 open the holding circuit to relay BC, whereupon relay BC will release since its original energizing circuit is open at armature 18, relay IA being locked operated. Upon the re-operation of relay I with the next battery and earth period of the busy signal a circuit may be traced to relay BR as follows: earth, armature 17 of relay B, armatures 59, 60 and 66, winding of relay BR to battery, thereby causing relay BR to operate and lock operated over armatures 68 and 17. Upon the operation of relay BR busy flash will be extended over conductor 69 and armature 12 to the lower winding of relay A, thereby causing relay A to operate intermittently to repeat the busy signal to the calling loop, while at the same instant the usual busy hold circuit is also completed at armature 70 via the lower winding of relay B in order to maintain that relay energized during the flash periods.

It must be mentioned at this point that in case it should be desired to hold the switches at the distant exchange operated during the busy condition, the dotted strap shown should be connected between terminals 71 and 72. 70 With the latter arrangement it will be readily appreciated that the operation of relay BR will cause a holding loop to be connected across the outgoing junction leads to the distant exchange. 75

Assuming now that all the outlets of the particular level dialled of the selector shown in Fig. 2 test busy; the wipers of the switch will then finally come to rest in the eleventh step position, whereat the cam springs S will be operated, thereby extending earth to the winding of relay CS which accordingly is operated. The operating winding of switching relay H is then short-circuited at armature 48 in order to render that relay inoperative, and the following busy flash circuit is then connected over the junction lines to the repeater: busy flash and earth over conductor 73', armature 33, lower winding of relay A2, armature 32, conductor 31, armatures 30 and 20, lower and upper windings of relay I in series, armatures 24, 19 and 25, conductor 26, armatures 27 and 29, upper winding of relay A2, armature 28 and low resistance 74 to battery. Similarly the following busy hold circuit is prepared to relay B2; battery over the hold conductor 75, lower winding of relay B2, armatures 38 and 36 to earth at armature 37 when relay A2 releases during the flash period. It will thus be appreciated from the foregoing description that a similar busy condition will again set up in the repeater circuit, from which the distant switches may be held or released dependent upon the strapping of terminals 71 and 72. 100 105

The calling subscriber hearing the tone or alternatively the operator seeing the lamp flash if the call is through a manual exchange will release, thereby allowing relay A in the repeater to restore which in turn effects the restoration of relay B. The release of relay B opens the holding circuit to relay BR, whereupon the latter relay opens the holding circuit to the distant switches at armature 25 so that all the apparatus taken into use is thus restored to normal in readiness for the next call. 110 115

We claim:

1. In a telephone system, a trunk line terminating in an automatic numerical switch, means responsive to impulses transmitted over the two conductors of said trunk line in parallel for operating said switch to connect with a succeeding switch, and means in said first switch for repeating subsequent impulses to operate said succeeding switch. 120 125

2. In a telephone system, a trunk line terminating in an automatic numerical switch, means responsive to impulses transmitted over the two conductors of said trunk line in 130

parallel for operating said switch to connect with a succeeding switch, and means in said first switch for repeating subsequent impulses over a loop circuit to operate said succeeding switch.

5. In a telephone system, an interoffice trunk line terminating in an automatic numerical switch, means responsive to impulses transmitted over the two conductors of said trunk line in parallel for operating said switch, means in said switch for repeating subsequent impulses to a succeeding switch, and means for completing a talking circuit through said first switch responsive to the encountering of a busy condition by the succeeding switch.

6. In a telephone system, a selector repeater arranged to be operated by impulses transmitted over the two line conductors in parallel, means in said switch for repeating subsequent impulses to succeeding switches to extend a connection to a called subscriber, and means for completing a talking circuit through said switch responsive to the encountering of a busy condition by a succeeding switch in the event such condition exists and to the answering of the called subscriber in the event the connection is completed without a busy condition being encountered.

7. In a telephone system, a trunk line terminating in a selector repeater, outgoing talking conductors for said switch, means for operating said switch responsive to impulses received over said trunk line, means for repeating subsequent impulses to extend a connection to a called subscriber, and means responsive to the encountering of a busy condition in the establishment of said connection for directly connecting said trunk line to said outgoing talking conductors.

8. In a telephone system, a trunk line terminating in a selector repeater, outgoing talking conductors for said switch, means for operating said switch responsive to impulses received over said trunk line, means for repeating subsequent impulses to extend a connection to a called subscriber, and means responsive to the encountering of a busy condition in the establishment of said connection in the event such condition exists and to the answering of the called subscriber in the event the connection is completed without encountering a busy condition for directly connecting said trunk line to said outgoing talking conductors.

9. In a telephone system, a selector repeater arranged to be operated by impulses transmitted over the two incoming line conductors in parallel, means in said switch for repeating subsequent impulses over a loop circuit to succeeding switches to establish a telephone connection, a relay, a circuit for said relay prepared when said switch connects with a succeeding switch and completed responsive to the reversal or discon-

tinuation of current over said loop circuit, whichever takes place first, and means responsive to the operation of said relay for completing a talking circuit through said switch.

8. In a telephone system, a selector repeater arranged to be operated by impulses transmitted over the two incoming line conductors in parallel, means in said switch for repeating subsequent impulses over a loop circuit to succeeding switches to establish a telephone connection, a relay in said switch operated over said loop circuit, means for releasing said relay responsive to the receipt of a busy signal from a succeeding switch, and means responsive to the release of said relay for extending said busy signal over said incoming line conductors.

9. In a telephone system, a trunk line, a repeater arranged to receive impulses over a calling loop and to repeat said impulses over the two conductors of said trunk line in parallel to establish a telephone connection, a relay, and means for operating said relay when the connection has been completed or when a busy condition has been encountered so that the connection cannot be completed.

10. In a telephone system, a trunk line, a repeater arranged to receive impulses over a calling loop and to repeat said impulses over the two conductors of said trunk line in parallel to establish a telephone connection, a relay, means for operating said relay responsive to the answering of the called subscriber or responsive to a busy condition at a succeeding point in the connection, and means controlled by said relay for reversing the battery connections to the calling loop or for connecting a busy signal to the calling loop dependent upon whether said relay was operated responsive to the answering of the called subscriber or responsive to a busy condition.

11. In a telephone system, a trunk line, an impulse repeater arranged to receive impulses over a calling loop and to repeat said impulses over the two conductors of said trunk line in parallel to establish a telephone connection, a relay arranged to be operated either when the called subscriber answers or when a busy condition is encountered in the establishment of the connection, means controlled by said relay when operated in response to the answering of the called subscriber for reversing the battery connections to the calling loop, and a resistance connected across the calling loop during said reversal.

12. In a telephone system, a trunk line, an impulse repeater arranged to receive impulses over a calling loop and to repeat said impulses over the two conductors of said trunk line in parallel to establish a telephone connection, a relay arranged to be operated either when the called subscriber answers or when a busy condition is encountered in the establishment

of the connection, and means effective only when said relay is operated in response to a busy condition for disconnecting said trunk line and for transmitting a busy signal to the calling loop.

5 13. In a telephone system, a two conductor trunk line, a simplex circuit including the two conductors of said trunk line in parallel, means for transmitting digit impulses over said simplex circuit to establish a telephone connection, and means responsive to the completion of said connection for converting said simplex circuit into a loop circuit including the two conductors of said trunk line in series.

10 14. In a telephone system, a two conductor trunk line, a simplex circuit including the two conductors of said trunk line in parallel, automatic switching apparatus at the distant 20 end of said trunk line; means for transmitting digit impulses over said simplex circuit to control said automatic switching apparatus in the establishment of a telephone connection, means responsive to the completion of 25 said connection for converting said simplex circuit into a loop circuit including the two conductors of said trunk line in series, and means controlled over said loop circuit for holding said automatic switching apparatus 30 operated.

15 15. In a telephone system, a two conductor trunk line, a simplex circuit including the two conductors of said trunk line in parallel, means for transmitting digit impulses over 35 said simplex circuit to establish a telephone connection to a called subscriber, means for converting said simplex circuit into a loop circuit including the two conductors of said trunk line in series when said connection is 40 completed, and supervisory means operated responsive to the reversal of current over said loop circuit when the called subscriber answers.

45 16. In a telephone system, a two conductor trunk line extending from an outgoing repeater in one exchange to automatic switching apparatus in a second exchange, a simplex circuit including the two conductors of said trunk line in parallel, means in said repeater 50 responsive to impulses received over a calling loop for repeating said impulses over said simplex circuit to control said automatic switch apparatus in the establishment of a telephone connection, means responsive to 55 the completion of said connection for converting said simplex circuit into a loop circuit including the two conductors of said trunk line in series, a relay in said repeater operated by reversed current over said loop 60 circuit when the called subscriber answers, and means controlled by said relay for reversing the current flow in the calling loop.

65 17. In a telephone system, a two conductor trunk line connecting an outgoing repeater and an incoming selector repeater, a simplex

circuit including the two conductors of said trunk line in parallel, means in said repeater responsive to impulses received over a calling loop for repeating said impulses over said simplex circuit, means responsive to impulses received over said simplex circuit for operating said selector repeater to extend a connection to a succeeding switch and for thereafter repeating the impulses over a loop circuit to the succeeding switch, and means responsive to the completion of the connection for converting said simplex circuit into a loop circuit including the two conductors of said trunk line in series, said loop circuit thereafter serving as a holding circuit for the selector repeater and succeeding switch and as supervisory circuit between said repeater and said selector repeater.

In testimony whereof we the said REGINALD TAYLOR and CHARLES EDMUND BEALE have 85 signed our names at Liverpool, England, this 19th day of December, 1929.

REGINALD TAYLOR.
CHARLES EDMUND BEALE.
